The ornamental design for a soleplate for laundry iron, as shown and described.

DESCRIPTION

FIG. 1 is a bottom front right perspective view of the first embodiment of a soleplate for laundry iron, showing my design;

FIG. 2 is a left view of the first embodiment thereof;

FIG. 3 is a right view of the first embodiment thereof;

FIG. 4 is a front view of the first embodiment thereof;

FIG. 5 is a rear view of the first embodiment thereof;

FIG. 6 is a top view of the first embodiment thereof;

FIG. 7 is a bottom view of the first embodiment thereof;

FIG. 8 is a bottom front right perspective view of the second embodiment thereof;

FIG. 9 is a left view of the second embodiment thereof;

FIG. 10 is a right view of the second embodiment thereof;

FIG. 11 is a front view of the second embodiment thereof;

FIG. 12 is a back view of the second embodiment thereof;

FIG. 13 is a top view of the second embodiment thereof; and,

FIG. 14 is a bottom view of the second embodiment thereof.
